UNITED STATES PATENT OFFICE.

JOHN L. WALLIS, OF ANDALUSIA, ALABAMA, ASSIGNOR TO WILLIAM C. FRITTER, OF
DOOTHAN, ALABAMA; NELLIE E. FRITTER ADMINISTRATRIX OF SAID WILLIAM
C. FRITTER, DECEASED.

HAY-PRESS.

1,348,911.

Specification of Letters Patent. Patented Aug. 10, 1920.

Application filed June 14, 1919. Serial No. 304,101.

To all whom it may concern:

Be it known that I, JOHN L. WALLIS, a citizen of the United States, residing at Andalusia, in the county of Covington and State of Alabama, have invented certain new and useful Improvements in Hay-Presses; and I do hereby declare the following to be a full, clear, and exact description of the invention, such as will enable others skilled in the art to which it appertains to make and use the same.

This invention relates to certain new and useful improvements in baling presses and contemplates more especially a manually operated press suitable for baling hay and other material.

An object of the present invention is the production of a baling press in which the material is rapidly and uniformly compressed by means of a hand operated mechanism of simple, durable and compact construction, capable of being easily and quickly repaired.

Another object of the invention is to produce a baling press embodying novel means for controlling the progressive movement of the follower or compressing member through the baling chamber, said means including oppositely arranged ropes or cables wound over a series of novel pulleys particularly disposed upon each side of the press, and having their respective ends connected to each side of the compressing member, a lever for imparting motion to some of the pulleys and adjusting devices for regulating the tension of the aforesaid ropes or cables.

With these and other objects in view the invention further consists in the combination and arrangement of the several parts hereinafter described and pointed out in the appended claims.

In the accompanying drawings which show an embodiment of my invention as now best known to me and in which corresponding reference characters designate similar parts,

Figure 1 is a side elevation of my improved baling press.

Fig. 2 is a top plan view thereof.

Fig. 3 is a detail sectional view through the operating lever and pulleys operated thereby.

Fig. 4 is a sectional elevation of the operating lever shown in Fig. 3.

55

Fig. 5 is a plan view of one of the multiple pulley supports and adjusting means therefor.

60

Fig. 6 is a side elevation of the multiple pulley support shown in Fig. 5.

65

Fig. 7 is an illustration of one of the single pulley blocks, and

65

Fig. 8 an illustration of a form of winged nut used upon the through or stay bolts of the press.

70

The present invention has been primarily designed for use in baling hay, and has been found particularly useful by that class of farmers whose quantity of production does not justify the installation of automatic presses.

The baling press comprises among other things a relatively light frame structure capable of being easily transported in any approved manner, a baling chamber and filling hopper, a compressing member and novel means for progressively moving the said compressing member, as will herein-after fully appear.

75

Referring to the drawings, the frame of the press is constructed of a plurality of planks 1, arranged to form the top 2, bottom 3, and opposite side walls 4. The planks are preferably spaced as shown leaving ample room for facilitating the tying of the bale in the usual manner.

80

The connecting cleats or bars 5 of the frame have secured to their inner faces the planks 1 by means of the bolt and nut connections 6. Stay or through bolts 7 having winged nuts 8 are also provided for effectively securing or strengthening the frame at the several places indicated, and may further be useful in regulating the pressure imparted to the bale, as will be understood.

90

While I have described this frame in the manner shown in the drawings, it will be understood that various changes in the construction and arrangement of the several parts may be made without departing from the spirit of the invention as herein set forth.

95

The filling hopper 9 is provided on the top of the frame and is in communication with the baling chamber 10 formed between the planks 1 of the frame.

100

The compressing member or follower block 11 is positioned within the baling chamber 10, and is operated to compress the material fed through the hopper by means 5 of a novel mechanism now to be described.

Extending from the compressing member 11 through slots in opposite side planks are eye bolts 12 to which are secured both ends of endless cables or ropes 13. Any desired 10 form of clamping device 14 may be used to secure this connection. There are two cables as shown, arranged upon opposite sides of the press, and as their positioning and other coöperating parts are identical the 15 same reference characters will be used to designate the respective elements thereof. Each cable 13 is designed to pass around a series of pulleys as shown in Figs. 1 and 2. The pulleys are particularly arranged 20 with relation to each other, and as shown in Fig. 1 are positioned substantially triangularly upon each side of the press. The cable 13 is peculiarly wound over these pulleys for purposes of positively and evenly 25 imparting motion to the compressing member. Beginning with the looped end 15, the cable 13 is passed around a pulley 16 secured to an operating shaft 17 to be presently described, and thence longitudinally of the 30 press to and around a pulley 18, thence again longitudinally of the press to and around another pulley 19 located beneath the aforesaid pulley 16, then again longitudinally of the press to and around another 35 pulley 20 aligned with the aforesaid pulley 18, and finally again longitudinally of the press back to the follower block and joined by the looped end 21 to the eye bolt 12.

As shown, the pulleys 18 and 20 are 40 mounted freely in the forked end 22 of a multiple pulley support 23 adjustably secured to the side of the press.

The pulley 16 is positively driven and is superimposed with relation to the pulley 19 45 which is freely rotatable on a stub shaft extending from a single pulley support 24 secured to the side of the press. By this particular triangular arrangement of the several pulleys and the peculiar passage of the cable 13 thereabout, an equal distribution of 50 the power for moving the compressing member is obtained, free from all strain and distortion. The positiveness of the driving connection through the pulley 16 is also increased so that tendency of the cable to slip 55 is eliminated.

The multiple pulley supports 23 comprise a rod having a threaded portion 25 arranged to pass through a sleeve or block 26 60 suitably secured by bolts 27 to the side of the press. A nut 28 is threaded upon the portion 25 and is designed to abut against one end of the sleeve or block 26 as shown. By this construction it will be apparent that 65 the multiple pulley support in which is

mounted the pulleys 18 and 20 can be adjusted with relation to the pulleys 16 and 19, thereby insuring the proper tension upon the cable 13 as will be readily understood. By adjusting each multiple pulley support 7 23 upon each side of the press the proper degree of tension can be easily imparted to the respective cables 13 connected to the extending eye bolts 12 of the compressing member or follow block 11. 7

The means for imparting motion to the opposite pulleys 16 for driving each cable 13 will now be described. Referring to Figs. 3 and 4 the pulleys 16 are secured upon the opposite ends of the driving shaft 17 which latter is suitably mounted in bearing boxes 29 secured to the frame of the press. Intermediate the ends of the shaft 17 is located a ratchet wheel 30 secured to the said shaft in any desired manner. Coöperating with 81 the ratchet wheel 30 is a reversible pawl 31 gravitatingly pivoted upon actuating lever 32. The lever 32 is provided with a forked end loosely mounted upon the shaft 17, and is also formed with a handle portion 33 relatively offset from the aforesaid forked end for facilitating a long stroke thereof with relation to the ratchet wheel 30 as will be understood. 91

In operation, it will be seen that as the 95 actuating lever 32 is moved in the direction as indicated by the arrow in Fig. 4, the pawl will operatively engage the teeth of the ratchet wheel 30 and impart a positive rotary movement to the driving shaft 17 which in turn will rotate the pulleys 16 thereby driving the cable 13. Upon the return movement of the lever the pawl will ride over the teeth inoperatively. This step by step or intermittent operation progressively 10 feeds the follower through the baling chamber until the material is sufficiently compressed, at which time the pawl 31 is reversed and the lever 32 actuated to return the follower block to repeat the baling operation. 11

Coöperating with the lever actuating mechanism is a locking or holding device 34 for purposes of checking any return movement of the follower block during the baling 111 operation. This device comprises a ratchet wheel 35 secured to the driving shaft 17, and a pawl 36 designed to operatively engage the said ratchet wheel upon a reverse direction of the said driving shaft 17. When returning 120 the follower after the baling operation, the pawl 36 is swung over and allowed to drag over the ratchet wheel 35 inoperatively.

In practice it requires but a few strokes of the actuating lever 32 to form a bale of 125 hay or other material, and likewise but few strokes to return the follower. From the foregoing it will be seen that I have produced an efficient and simply constructed baling press, in which a uniform pressure is 130

derived from the compressing member or follower block, and the power imparted to the said follower block evenly distributed and easily obtained through the manipulation of a simply constructed actuating lever.

It will be understood that various changes in the proportion and form of the several parts herein described may be made without departing from the scope of my invention as set forth in the claims.

I claim:

1. A baling press having a chamber formed therein, a compressing member adapted to move within the said chamber, a cable having each end thereof attached to the said compressing member, a series of oppositely arranged pulleys over which the said cable passes, means including screw-threaded rods for longitudinally adjusting some of said pulleys, and means for imparting rotary movement to another of said pulleys for moving the compressing member in the chamber.

2. A baling press having a chamber formed therein, a follower block adapted to move within the said chamber, arms extending from said follower block, oppositely arranged cables having each end thereof attached to the said arms, superimposed pulleys arranged upon opposite sides of the press at one end thereof, and other pulleys located upon each side of the press at the other end thereof, over all of which pulleys the aforesaid cables pass, means for longitudinally adjusting said second mentioned pulleys, and means for driving the upper-

most superimposed pulleys for moving the follower block within the chamber.

3. A baling press having a chamber formed therein, a compressing member adapted to move within the said chamber, a cable having each end thereof attached to the compressing member, a series of pulleys over which the said cable passes at each end of the press, means for imparting movement to the said pulleys for moving the compressing member, and adjusting means at one end of the press, said means including a pulley support having a screw-threaded end for regulating the tension of the aforesaid cable.

4. A baling press having a chamber formed therein, a compressing member adapted to move within the said chamber, a cable having one end thereof attached to the compressing member, a series of pulleys over which the said cable passes at each end of the press, means for imparting movement to the said pulleys for moving the compressing member, and adjusting means at one end of the press, said means including a pulley support having a screw-threaded end, a sleeve in which the pulley support is longitudinally movable and a nut threaded on said screw-threaded end and adapted to bear against one end of the said sleeve.

In testimony whereof I affix my signature, in presence of two subscribing witnesses.

JOHN L. WALLIS.
